James C. Winslow INVENTOR

UNITED STATES PATENT OFFICE

144,474

DESIGN FOR A PENCIL LEAD HOLDER

James C. Winslow, Inglewood, Calif.

Application July 23, 1945, Serial No. 120,909

Term of patent 14 years

(Cl. D74—24)

To all whom it may concern:

Be it known that I, James C. Winslow, a citizen of United States of America, residing at Inglewood, in the county of Los Angeles, State of California, have invented a new, original, and ornamental Design for a Pencil Lead Holder, of which the following is a specification, reference being had to the accompanying drawing, forming a part thereof.

I claim:

The ornamental design for a pencil lead holder, substantially as shown and described.

JAMES C. WINSLOW.
